Patented June 13, 1916.

UNITED STATES PATENT OFFICE.

GEORGE B. WILCOX, OF SAGINAW, MICHIGAN.

SWITCH-LOCK.

1,136,636.

Specification of Letters Patent. Patented June 13, 1916

Application filed October 19, 1915. Serial No. 53,722.

To all whom it may concern:

Be it known that I, GEORGE B. WILCOX, a citizen of the United States, residing at Saginaw, in the county of Saginaw and State of Michigan, have invented certain new and useful Improvements in Switch Locks; and I do hereby declare the following to be a full, clear, and exact description of the invention, such as will enable others skilled in the art to which it appertains to make and use the same.

This invention relates to electric switches and pertains more particularly to locking devices for a particular type of well-known automobile switch.

Switches of the type to which my invention is applicable are ordinarily made with a locking device actuated by a pronged lever that is inserted in the switch to turn it, the lever remaining in the switch while the contacts are closed, and being removable from the switch only when the contacts are broken. A serious disadvantage of this construction, as found in practice, is that the pronged lever can be easily duplicated by unauthorized persons, and the switch may even be operated by any other suitably pronged tool.

My improvement has for its object to provide a simple and inexpensive anti-tampering locking device that can be easily and quickly substituted for the pronged lever and face plate ordinarily furnished with the switch, thereby converting the switch into one that can not be opened except by the owner's key. To apply my improvement to such switches the only tool required is a screw-driver; no mechanical skill is needed, and the device is so constructed that the change can be made without in any way altering or disturbing the mechanism of the switch.

The improvement also embodies a simple means whereby the locking device is itself secured against removal from the switch case when the owner's key is out of the lock, and access to the switch mechanism can not be had without breaking or damaging the switch mechanism, even though the fastening screws be removed.

With the above and certain other objects in view, which will appear later in the specification, my invention consists in the devices described and claimed and the equivalents thereof.

In the drawings, Figure 1 represents a

part-sectional elevation of a switch case of the type referred to, to which my improved locking device is applied. Fig. 2 is the front view of a case showing the stop arm 20 the contact device. Fig. 3 is a rear view of the plate on which my improved locking device is mounted, showing the hook that engages the contact arm when the arm is in its neutral position, to prevent removal of 65 the lock and plate. Fig. 4 shows the locking device and the switch case of Fig. 1, separated.

1 is the switch case, within which is mounted a pivoted stop arm 2 of vulcanized fiber, the arm having a vulcanized fiber hub 3, to the lower part of which is secured the metallic contact members of the switch mechanism. These contact members operate in the lower part, 1^a, of the case 1, but are omitted from the drawing for the sake of clearness, as they form no part of my invention. The hub 3 carries on its outer face a slotted plate 4 to receive the prongs of the usual switch-operating handle, but in my improvement these prongs (5) are mounted on the barrel of a cylinder, or equivalent lock 7 having an individual key 6.

8 is a plate adapted to be substituted in place of the flat plate which is regularly furnished with this type of switch as a closure for the case 1. The lock 7 is secured to the plate 8 in any suitable manner, but I prefer to form the plate with an outwardly-projecting cylindrical barrel 13, the lock being received in the barrel, as shown in Fig. 1 and secured to the barrel by soldering or otherwise. The plate 8 is secured to the case 1 by screws 9 received in threaded bosses 9^a, 9^b, 9^c formed in the case 1.

The stop arm 2 when turned to the position indicated by dotted lines at 10 and 11, Fig. 2, is stopped by the projections 9^b or 9^c, thus properly limiting the throw of the switch mechanism located in the space 1^a. When the arm 2 is in its central position, the key 6 may be removed from the lock 7, but when the arm is in either of the positions 10 or 11 the key can not be removed.

To secure the plate 8 against unauthorized removal, and to thereby prevent access to the switch mechanism when the key is out of the lock, that is, when the stop arm is in its central position, I secure to the plate 8 an inwardly projecting and downwardly bent hook-member 12 that projects into the case 1 between the case and the extremity

of stop arm 2 and extends downwardly in the rear of the path of travel of arm 2. The arm 2 travels freely from right to left through the hook, but when the stop arm 5 is in its central position, the downwardly-extending flange of hook 12 lies directly behind the arm 2. Removal of the plate 8 is thereby prevented, even though the screws 9 be taken out, because if it is attempted to 10 forcibly pry the plate away from the case the vulcanite stop arm 2 will be broken, or the switch will otherwise be damaged.

To apply the locking device to an existing switch, the stop arm 2 is first turned to 15 either of the positions 10 or 11. The screws 9 are taken out and the flat face-plate, which forms a cover for case 1, is removed, exposing the arm 2 and the switch mechanism. Plate 8 with its lock 7 and hook 12 is then 20 put in place and secured with the same screws 9 that were employed to fasten the original plate. Thereafter, when the owner's cylinder lock key 6 is inserted and turned to the right or left, the switch will be 25 turned to "battery" or "magneto" position. The locking device can be removed by merely taking out the screws 9 and lifting off the lock and plate, as shown at the left of Fig. 4, when the arm is turned to right 30 or left, but when the arm is central the locking device can not be removed.

By the means above described, I have produced a simple, inexpensive, yet effective locking device that can be easily and quickly 35 substituted for the usual face plate, by persons without mechanical skill, and the device when once in place can not be removed without damage to the switch, unless the owner's key is in the lock. It will be noted 40 that the securing of the locking device to the case is accomplished without any change in the existing switch, being performed by an already existing part of the switch mechanism, namely, the stop arm 2.

45 Having thus described my invention, what I claim and desire to secure by Letters Patent is:

1. In combination, a switch case, a pivot-

ally mounted stop arm secured within said case, a removable cover, a lock carried by 50 said cover and adapted to actuate said stop arm, a securing member fixed to said plate, said member projecting inwardly between the wall of the case and the extremity of said stop arm and having its inner end bent 55 downwardly, its downwardly projecting part located in the rear of said stop arm when the arm is in its central position, for the purposes set forth.

2. An anti-tampering locking attachment 60 for electric switches having a switch case and a radially projecting stop-arm pivotally secured therein, said attachment comprising a face plate adapted to be removably secured to said case, an individual-key lock 65 mounted on said plate and adapted to actuate the stop arm of said switch, an inwardly and downwardly projecting hooked member secured to said plate, said hooked member arranged to permit said stop arm 70 to move freely from side to side, but adapted to register with the stop arm to prevent removal of the plate and lock when the stop arm is in central position.

3. An anti-tampering locking attachment 75 for electric switches having a switch case and a radially projecting stop-arm pivotally secured therein, said attachment comprising a face plate adapted to be removably secured to said case, an individual-key lock mounted 80 on said plate and adapted to actuate the stop arm of said switch, a member carried by said plate and disposed in the rear of the plane of movement of said stop arm, said member adapted to permit the stop arm to 85 move freely from side to side, but arranged to register with the stop arm to prevent removal of the plate and lock when the stop arm is in central position.

In testimony whereof, I affix my signature 90 in presence of two witnesses.

GEORGE B. WILLCOX.
